UNITED STATES PATENT OFFICE.

CHARLES S. MOONEY, OF DETROIT, MICHIGAN.

RADIATOR.

1,265,940.

Specification of Letters Patent.

Patented May 14, 1918.

Application filed September 5, 1916. Serial No. 118,370.

To all whom it may concern:

Be it known that I, CHARLES S. MOONEY, a citizen of the United States of America, residing at Detroit, in the county of Wayne 5 and State of Michigan, have invented certain new and useful Improvements in Radiators, of which the following is a specification, reference being had therein to the accompanying drawings.

10 In the construction and operation of radiators for automobiles it is desirable that they present a radiating surface that is large in proportion to the water columns and contain a minimum of joints whereby their efficiency is enhanced and their liability to leakage diminished. It is desirable also that the parts be so disposed as to afford a certain flexibility to avoid injury from jars and vibrations.

20 This invention relates to radiators wherein a very large air radiating surface in proportion to the water columns is combined with a simplicity of construction that minimizes the joints and number of parts and 25 provides for a greater efficiency because of the manner in which the air passages baffle the air current, while the construction is sufficiently flexible or yielding to resist injury from the shocks and vibrations incident 30 to unfavorable service conditions.

The invention consists in the matters hereinafter set forth and more particularly pointed out in the appended claims:

In the drawings,

35 Figure 1 is a view in front elevation, largely diagrammatic, of a radiator embodying features of the invention;

Fig. 2 is a view in detail showing one element of the honeycomb or grille and one 40 method of connecting the unit with the top and bottom headers thereof;

Fig. 3 is a view in front elevation of a portion of an element;

Fig. 4 is a view in cross section of the element taken on or about line IV-IV of 45 Fig. 2;

Fig. 5 is a view in detail showing the upper portions of several elements and associated wall of a header;

50 Fig. 6 is a view of a blank for a slight modification of the element;

Fig. 7 is a view in cross-section of this modification;

Fig. 8 is a view in detail of another modification of the element; and Fig. 9 shows another form.

Referring to the drawings, a frame 1 of standard type has the usual upper header 2 and lower header 3, in which a panel of water column elements, or the so called "grille" or "honeycomb" is placed.

This honeycomb consists of a series of upright water sections mounted between the lower wall 4 of the upper header and the upper wall 5 of the lower header in spaced 65 relation to provide the requisite air circulation. Each element has a sheet metal side 6 having impressed thereon a tortuous channel with substantially horizontal loops 7 extending from margin to margin and terminating at the upper end portion in an upright arm 8 and at the lower end portion in a corresponding downturned arm 9. A companion side 10 that is reversely impressed, is secured against the part 6 in 75 such manner that the embossed portions or impressions are in register while the margins outside of the impressed portions are intimately united by any suitable form of non-leakable joint. This may be effected 80 by appropriate spot-welding, by brazing, soldering or in any other preferred manner.

The members are of a width in proper proportion to the walls 4 and 5 of the headers. The channels or passages formed by the 85 impressions are in communication with the interiors of the headers through any preferred connections. Nipples 11 inserted in the arms 8 and 9, and headed down in openings in the walls through which they are 90 passed, afford one such form of union.

The elements may each be formed of the separate sides 6 and 10, or a single blank 12 may be provided with reverse impressions 13, and may be folded on its axis of symmetry 14, with suitable hermetical joinder of the contacting faces.

In Fig. 8, provision is shown for an element that has not only the lateral elasticity afforded by the arrangement of parts just described, but also longitudinal extensibility within a certain range. A blank 15 with impression 16 is slotted as at 17 between the loops. The element formed of such sides is longitudinally elastic, and accommodates 105 itself to slight variations in the frame while being mounted therein and also successfully resists vibrations and shocks without leakage.

While the impressions herein shown provide an efficient channel, different requirements of service and conditions of use are

of course met by suitable proportion and design of such passages, the form herein illustrated being merely one of a number which are efficacious in suitably circulating the water in contact with large surfaces cooled by contact with the atmosphere. One of the plates may be plain as shown in Fig. 9.

As a result of this construction, a radiator 10 is obtained that presents a very large air-cooled surface in proportion to the water channels and effectively baffles the air currents to increase and lengthen the period of contact with the radiating walls. The portions of the plates around the impressions 15 preclude the necessity of other fins, and therefore simplify the structure without impairment of the efficiency of the radiator. The elements are elastic and slightly yieldable, and this feature, together with the small number of necessary joints, minimizes 20 any leakage under even severe service.

Obviously, changes in the details of construction may be made without departing 25 from the spirit of the invention, and I do

not care to limit myself to any particular form or arrangement of parts.

I claim as my invention.

1. In a radiator, a water column element comprising opposed sheet metal sides with 30 mating impressions forming a water passage through the element, the margins of the sides being slotted to permit limited longitudinal extension of the element.

2. In a radiator, an upper header, a lower 35 header and a series of water column elements connecting the headers, each consisting of a pair of sheet metal sides oppositely impressed to form a tortuous, continuous and uninterrupted water channel from end to end 40 thereof, the exterior conformation of the sides forming air-baffling projections and radiating fins having slots affording lateral and longitudinal elasticity to the element.

In testimony whereof I affix my signature 45 in the presence of two witnesses.

CHARLES S. MOONEY.
